UNITED STATES PATENT OFFICE.

HERMAN KRASNE, OF OMAHA, NEBRASKA.

ROTATABLE DISPLAY-RACK.

937,155.

Specification of Letters Patent.

Patented Oct. 19, 1909.

Application filed July 29, 1909. Serial No. 510,163.

To all whom it may concern:

Be it known that I, HERMAN KRASNE, a citizen of the United States, residing at Omaha, in the county of Douglas and State 5 of Nebraska, have invented certain new and useful Improvements in Rotatable Display-Racks, of which the following is a specification.

This invention relates to improvements in 10 rotatable display racks, and has for its object to provide a rack of this class which will be reliable in operation, and to comprise parts which may be conveniently constructed and assembled.

15 The invention has reference to a rotatable structure the parts of which are so joined as to be durable in wear and convenient for the display of garments or fabrics, and whereby a large number of garments or articles may 20 be suspended and displayed within a limited space.

With these and other objects in view, the invention comprises a novel combination and arrangement of parts as described herein, 25 pointed out by the appended claims and as illustrated in the drawing, it being understood that changes in form, size, proportion and minor details may be made within the scope of the claims, without departing from 30 the spirit or sacrificing any of the advantages of the invention.

In the drawing, Figure 1 is a perspective view of a rotatable display rack, embodying my invention, the supporting shaft being 35 partly broken away. Fig. 2 is a view in longitudinal section of the pivot post and rotatable sleeve, parts connected therewith being partly broken away or in section. Fig. 3 is a plan view of the annular bearing 40 plate, and arms mounted thereon. Fig. 4 is a side view of one of the holders or sustaining arms. Fig. 5 is a view of a garment holder.

45 Referring now to the drawing for a more particular description, numeral 5 indicates a standard or upright having threaded ends, its lower end being provided with a support or base 6 whereon the standard may be maintained in a vertical position.

50 I employ the pivot post 7 having exteriorly threaded terminals, and by use of the threaded coupling-sleeve 8 the pivot post may be secured upon the upper end of and in alinement with the standard. I provide the rotatable sleeve 9 adapted to have a seating 55 upon post 7 and having expanded termini-

nals to provide at its upper end the annular bearing plate 10, and at its lower end the annular enlargement or base 11.

I provide supporting arms 12 having their inner ends secured upon the bearing plate by bolts 13, and they extend outwardly substantially at right angles from sleeve 9. Arms 12 are preferably arranged in pairs, the arms of a pair being in alinement so that the weight will be equally distributed, said arms being spaced apart uniformly as to distance.

At 14 are indicated links or inclined braces having their lower ends mounted upon the annular base 11 of the sleeve, and preferably having a threaded connection of said ends in apertures 15 formed in this base, the upper ends of these inclined brace rods traversing openings formed in the outer terminals of arms 12, and secured by screw-nuts 16.

As thus described the parts are separable, may be readily assembled or disassembled, and may be conveniently packed to occupy a limited space for shipment, head 17 also having a threaded connection with standard 5. Tubular material is preferably employed for the standard, pivot-post and sleeve, and for the terminal upright 18, so that the parts will not have undue weight.

Braces 14 are disposed in vertical alinement with arms 12, and a containing space is therefore provided between said arms, convenient for displaying garments. At uniform, longitudinal intervals in arms 12 are provided vertical apertures 19. I provide sustaining-links 20 each having an angular terminal 21 for seatings in apertures 19, the opposite ends of the links being curved to provide keepers or hooks 22. The links may therefore swing horizontally, and upon keepers or hooks 22 may be seated loops 23 of garment holders 24.

By the described construction a large number of garments may be supported within a small compass, and as is obvious, the number of apertures 19 may be increased, as desired, and thereby links 20 may be mounted nearer to each other, also arms 12 may have any suitable length, and the number of these arms may be increased.

While in Fig. 1 I have shown links mounted upon only one of arms 12, it will be understood that all of said arms are to be employed for the mounting of said links, for the purpose of displaying garments which

may hang vertically between arms 12, and the parts of the device coöperate to advantage, the space between arms 12 being ample, and links 20 swinging horizontally at any 5 desired angle.

In order that links 20 may be adequately supported to sustain any weight applied to hooks 22, I employ the curved sustaining arms indicated at 25. The inner end of one 10 of said arms may be seated upon the inner end of one of arms 12 and held by bolt 13, the outer end being secured upon the outer terminal of an adjacent supporting-arm 12; the inner ends of said arms 25, by this construction, are supported upon the annular bearing-plate of the sleeve, and a strong and rigid mounting provided for said arms; they 15 provide a reliable support upon which links 20 may rest and may slide when said links have their horizontal swinging movements. While the degree of curvature of the sustaining-arms is not particularly important, the curvature should be such that the contact of the links upon said sustaining-arms 20 will not be too near to hooks 22 during the movement of links 20. The inner ends of supporting-arms 12 are partly cut away to provide lugs 26 for bearings upon the periphery of bearing-plate 10, and the bearings of these lugs assist materially in sustaining said supporting-arms 12 in a horizontal position.

It will be noted that the angularly bent ends 21 of links 20 have reduced terminals to 35 provide annular stops 27, and when the angular ends of said links 20 are inserted in openings 19 of arms 12, said links are sustained in a plane above arms 12, stops 27 resting upon the upper surface of the arms, and this is a 40 desired construction since the curved sustaining-arms are likewise disposed in a plane above arms 12, and are therefore disposed in a position to support links 20, as above described.

45 The horizontal plane occupied by links 20 is normally above curved sustaining-arms 25; the links therefore are normally out of contact with said arms, and for this reason the device is operative to prevent disengagement 50 of the links when heavy articles are supported by the free ends of links 20. The reduced ends 21 of links 20 are adapted to have a close fitting within openings 19, and when heavy articles are suspended upon holders 24, links 55 20 are bent downward, and disengagement is prevented for the reason that there is a binding contact of angular ends 21 within openings 19; and this contact continues while

links 20, have their swinging movements, only a part of the weight being sustained by 60 arms 25.

Having fully described the several parts and their uses, a further explanation relating to operation or usefulness is not required.

What I claim as new and desire to secure 65 by Letters Patent is,—

1. A display rack, comprising an upright support, a rotatable part mounted upon the upright; radially-disposed, horizontal supporting-arms rigidly mounted upon the rotatable part, and provided at longitudinal intervals with vertical apertures; and a plurality of holding-links, each having an angular terminal adapted to traverse one of said vertical apertures of a supporting-arm, its 75 opposite terminal being provided with a keeper.

2. A display rack comprising a vertically disposed supporting part, a sleeve mounted rotatably upon the supporting part; radially 80 disposed, horizontal supporting-arms rigidly mounted upon the rotatable sleeve, and a plurality of holding-links mounted for horizontal rotation upon said supporting-arms.

3. In combination, a display rack comprising a support; an upright upon the support; a pivot-post disposed in vertical alinement with and mounted upon said upright; a sleeve mounted upon the pivot-post and having an annular bearing-plate upon its upper 90 terminal, its lower terminal provided with an annular enlargement; supporting-arms having their inner ends secured upon the bearing-plate and extending radially and horizontally therefrom, said arms being provided at longitudinal intervals with vertical apertures; links having their lower ends mounted upon the annular enlargement of said sleeve, each of said links being disposed inclinedly in the vertical plane of a supporting-arm, its upper end being in engagement with the outer terminal of said supporting-arm; curved sustaining arms having their inner ends supported by said bearing-plate, 95 their outer ends secured to said supporting-arms; a plurality of holding-links adapted to have seatings upon said sustaining-arms and provided with angular terminals engaging within the apertures of said supporting-arms.

100 In testimony whereof I have affixed my signature in presence of two witnesses.

HERMAN KRASNE.
